Attorney.

UNITED STATES PATENT OFFICE.

FREDERICK JOHNSON, OF BUFFALO, NEW YORK.

CAR-COUPING.

SPECIFICATION forming part of Letters Patent No. 399,333, dated March 12, 1889.

Application filed December 19, 1888. Serial No. 294,054. (No model.)

To all whom it may concern:

Be it known that I, FREDERICK JOHNSON, a citizen of the United States, residing in Buffalo, in the county of Erie and State of New York, have invented certain new and useful Improvements in Devices for Operating the Locking-Catch of a Car-Coupling, of which the following is a specification.

The object of my invention is to render more complete and convenient the operation of car-couplings of that class shown in the Barnes patent, No. 337,650, or any of that class having a similar construction, and it relates to a novel means for operating the swinging catch for locking or unlocking the pivoted coupling-arms, all of which will be more fully and clearly hereinafter described and claimed, reference being had to the accompanying drawings, in which—

Figure 1 is a top view of a suitable car-coupling having my invention combined therewith. Fig. 2 is a front elevation of a portion of a car, showing a similar view of the device for operating the locking-catch and holding it in position until it is desired to release it, also a front elevation of the draw-head and coupling. Fig. 3 represents a front elevation, showing a modification of the operating and holding device, and Fig. 4 is a detached side elevation of the holding device.

In said drawings 1 represents a suitable car-coupling to which my invention is adapted. The draw-head 2 is preferably made of cast-iron, as being the best and cheapest material. It is made hollow in the usual way, and is provided with the pivoted angular-shaped coupling-bar 2^a, secured to the draw-head by the pin 3. When this coupling-bar is closed or secured to another coupling, it is in the position shown in Figs. 1 and 2. In Fig. 1 it is shown as when locked in position, the inner portion of the coupling-bar 2^a being shown by dotted lines 4. The locking-catch is also shown by the dotted lines 5 in Fig. 1. It is pivoted to the draw-head by a pin, 6, so as to swing thereon.

These kinds of car-couplings are usually made with an inclined guideway at the top and bottom or above and below the locking-catch 5 shown in Fig. 1, so that when the catch is drawn upward it swings back or around on the pivot 6 out of the way of the

end 7 of the coupling-bar 2^a, so as to allow it to swing open and uncouple, and when it drops down it swings around so that one of the notches 8 (see Fig. 1) catches the end 7 of the coupling-bar 2^a, and thereby locks it; but as the construction and operation of this kind of car-coupling are old and well known, a further description here is unnecessary.

With these kinds of car-couplings during the operation of uncoupling it is necessary that the locking-catch should not only be lifted up, but it should be also held up until the uncoupling is effected, and the object of my invention is to do this, as it cannot be conveniently done by hand.

At a convenient distance above the coupling at the end of the car I secure in the usual way by screws a cam-plate, 9. This cam-plate is usually made of cast-iron, but it may be made of cast-steel, malleable or wrought iron, or of any suitable material. The upper portion of this plate is provided with an inclined camway, 10, as shown in Fig. 1, or with two inclined camways, 10, as shown in Fig. 3. It is also provided with the two bearings 11, in which is mounted an uncoupling-bar, 12, having a handle, 13, by which it is operated. Rigidly secured to the uncoupling-bar is an outwardly-projecting arm, 14, and to the end of the arm 14 is secured a chain, 15, having its opposite or lower end pass through a hole in the top of the draw-head and secured to the locking-catch 5.

From this description it will be seen that by moving the handle 13 and turning the uncoupling-bar the locking-catch may be either lifted or lowered, and that by drawing the uncoupling-bar longitudinally to one side, so as to move the arm 14 sidewise up along the inclined camway, the locking-catch may be lifted up and held in such position until released by pushing the uncoupling-bar in the opposite direction, and thereby permitting the locking-catch to drop into its locking position.

I claim as my invention—

A device for operating the locking-catch of a car-coupling, consisting of a stationary cam-plate, 9, having an inclined camway opening between the bearings, in combination with an uncoupling-bar mounted in said bearings so as to permit both a turning and a longitudi-

nal movement, and provided with an arm for operating it, and an arm, 14, rigidly connected to and projecting out from the uncoupling-bar and connected by a chain to the locking-catch 5 of a car-coupling, whereby a simultaneous longitudinal and turning movement of the uncoupling-bar will lift the arm 14 as it moves up the inclined camway and hold it and

the locking-catch in their upward position until it is necessary to release them, substantially as described.

FREDERICK JOHNSON.
